UNITED STATES PATENT OFFICE.

ALEXANDER SIMON, OF MUNICH, GERMANY.

HIGH-TENSION INSULATOR.

Application filed July 10, 1925, Serial No. 42,695, and in Germany October 12, 1922.

The high tension insulators used at present do not utilize the insulating capacity of the material to the best advantage; and, moreover, have certain other defects which impair their dependability. At certain points or portions on the insulator, static fields of high intensity are liable to be formed, either normally or after exposure to moisture, so that the air surrounding the said insulator is subjected locally to excessive stress. This stress may increase until glow or brush discharges occur which may lead to regular discharges. These latter discharges occur far below the potential for which the insulator is rated, and may cause the insulator to break down because of local development of heat.

These defects are known, and endeavours have been made to overcome them by giving the insulator body a special shape, or artificially influencing the electric field. Examples of insulators of this kind are, for instance, the bell insulator and the metal-shielded insulator. These devices are, however, merely modifications of standard types, involving no radically new principle.

The present invention has for its primary object eliminating the aforesaid defects in insulators by diminishing the intensity of the field existing between the electrodes, and by providing for a continuous distribution of that part of the field between the electrodes which lies within the insulator.

If the intensity of the electric field is uniform, the potential gradient is uniform also.

The reduction of the intensity of the field is attained by increasing the distance between the electrodes, this being effected by providing an umbrella shaped insulating

body surrounding an axially disposed electrode, with a convexly curved metallic cap covering said insulating body and being so arranged as to contact the rim thereof, and as to include a gap with said body, which

increases from the rim of said cap toward the central axis of said body and is filled with an insulating medium, preferably with a gaseous medium. In this way, a consider-

able distance between the inner electrode and the cap forming the second electrode may be obtained without the necessity of using very thick insulating parts which are difficult to manufacture in good qualities. The

cap provides for the protection from rain and affords a high mechanical strength. 55

The provision of a uniform field distribution, and of a corresponding fall of potential between the electrodes is attained by giving the insulator and electrodes a particular shape, the chief features in these respects being that the electrodes, that is to say the bracket and the metallic cap, used sometimes to support a conductor, are so shaped and arranged with respect to each other and the interposed insulator that abrupt changes of shape between adjacent parts are avoided, and that the shortest distances from any given or selected point of the cap to the other electrode are proportioned in accordance with the dielectric constant of the insulating means traversed by the respective lines of such distances. 60

Where the lines of distance extend through two different dielectrics, as porcelain and air, the calculation of these distance lines must be based upon the corresponding mean or average values of the individual dielectric coefficients. If, for instance, a given distance line L extends through the length L_1 within a medium with the coefficient E_1 , and through the length L_2 within a medium with the coefficient E_2 , the mean value EM in question is, according to well known principles, 70

$$EM = \frac{(L_1 + L_2) \times E_1 \times E_2}{L_2 \times E_1 + L_1 \times E_2}$$

it being $L = L_1 + L_2$. According to the invention, the parts are so shaped that the ratio $L:EM$ is substantially equal for all distance lines which extend within the insulator. 90

An embodiment of the invention designed according to the principles set forth in the preceding paragraphs is shown by way of example in the accompanying drawing, in which:—

Fig. 1 shows an elevation partly in section of a pin-type insulator; 100

Fig. 2 shows the invention applied to a suspended insulator.

Referring to Fig. 1, the umbrella shaped insulator body v is formed of any appropriate insulating material and is provided with a bore to receive a pin a which may be made of metal. A metallic cap h is shaped 105

- 2 to engage the insulator body at s and overhangs the body by a considerable distance as shown at t . The conducting wire b is not attached directly to the insulator body, 5 but is attached to the cap h , forming an electrical connection therewith. The function of the cap h is to protect the insulator body from rain and by virtue of its conducting properties to distribute the area of high potential rather than allowing it to remain concentrated at the conductor b . The inner surface of the bore is coated in a known manner with a conducting layer f forming the inner electrode from which the 10 electric field lines extend to the cap forming the outer electrode. As will be noted in the drawing, the upper surface of the insulator body is slightly convex, while the top of the metallic cap is more convex, so that the 15 thickness of the gap between the two elements increases from the rim to the axis of the insulator. The gap is filled with any suitable insulating medium, preferably with air.
- 15 The cap and the body are in fact so designed that the ratio between the dielectric coefficient along a distance line extending from any point on the cap to the pin a , and such distance line is a constant for all such 20 distance lines which lie within the insulator. For instance, along the distance line i_4 extending through a layer of air and a thicker layer of porcelain, the dielectrical coefficient has a different value from that measured 25 along the line i_5 extending through a thinner layer of porcelain and a thicker layer of air, the lengths of both these lines having the same ratio as the respective dielectrical coefficients.
- 30 30 The insulator body is provided with an annular flange d designed to reinforce the body against breakage, and to protect the body against rain. In some cases it may be desirable to employ several flanges like d .
- 35 35 The body is also provided with a skirt e to prevent surface discharges. The skirt e serves a purpose similar to that of flange d and may be duplicated according to the conditions for which the insulator is designed.
- 40 40 It will be seen that the apparatus of the present invention prevents the concentration of electrostatic charges which might cause discharges over the surface as a result of ionization of the adjacent air.
- 45 45 A sufficiently uniform field distribution also arises when the individual distances measured at neighbouring places show only gradually increasing deviations from the values of ratio of the dielectric constant.
- 50 50 There is also to be considered the circumstance that the singly measured distances do not coincide accurately with the path or course of the lines of force as these are subjected to refraction at the boundary surface of two dielectrics i_1 i_2 i_3 and i_4 and i_5 are distance

lines which are in the same proportion to the dielectrical coefficient measured along those lines. The line i_4 is a broken line representing the course of a field line subjected to refraction.

70 In regard to the known metal-shielded insulators my invention resembles them in respect of using the metallic cap for artificially influencing the electric field, but it is also employed for other and quite different purposes in other and quite different ways. With the known insulators mentioned in which the metallic cap is simply placed upon the ordinary insulating body and forms a substitute for the uppermost bell, the intention is merely to fling away the drops of rain from the rim. The field existing between the bracket and the bell cap is not diminished. A substantial uniformity of the field distribution is not attained. In contradistinction thereto a considerably better uniformity and reduction of the electric field is attained by means of a particular shape of the metallic roof, in combination with a particular shape of the insulating body.

80 90 An essential feature as regards the effect obtained by this improved insulator resides also in the feature that in the case of a change of the difference of potential existing between the electrodes the field existing between them is varied, it is true, as regards its strength, but not as regards its extensional distribution.

95 The insulator illustrated in Fig. 1 may be used also as a suspended insulator in that the metal cap of one insulator is connected in any suitable manner with the bracket or the equivalent therefor of the adjacent insulator, and so on. The electric properties of the insulator are not materially changed thereby.

100 The modification shown by Fig. 2 is an insulator of the suspended type comprising an umbrella shaped insulating body k , the thickness of which decreases from the center to the rim. The upper surface may be truly conical or slightly curved so as to form an arched body which has a downwardly directed rim r as its base. By this construction the arched insulating body acts like an arched bridge which is supported by its bases. A central draw-bolt w constituting the inner electrode, extends through the body k ; its upper portion is 110 conical, terminating in a flange, and is covered with a layer l of insulating material such as rubber. The insulator k is provided with a central aperture or internal bore to receive the draw-bolt or member w . A lower insulating skirt x fits snugly against the member k , being held in position by an internally threaded clamp m , an annular metallic member n being interposed between clamp m and member x .

115 120 125 130 A metallic cap h constituting the second

electrode covers or fits over the entire insulator and supports the insulator body k by engaging the rim thereof. In this manner the cap maintains the insulating body in position even if the said body is broken because the broken parts act as members of an arch and are held in place by the bases or in the present construction by the rim r .

The suspension means comprises the usual 10 knob o and the loop p . The joints between the cap h , the body k and the skirt x are filled, prior to assembly, with insulating cement of any suitable composition.

The shape of the cap is designed as follows: The radial distance line i_6 between the 15 rim of the umbrella shaped insulating body k and the inner electrode w , is calculated according to well known principles in such a manner that a puncture of the insulator 20 along this radial distance line extending within the insulating material cannot occur. The dielectric coefficient of this material may be e . The axial distance line i_7 between the top of the cap and the inner electrode w 25 measured along the axis is given by the equation:

$$i_7 = i_6 \times \frac{e}{e_1}$$

30 wherein e_1 is the mean dielectric coefficient of the media filling the space between the inner electrode and the cap h . The height and the diameter of the cap being determined, the profile of the cap is so designed 35 that the gap included between the cap and the insulating body increase continuously from said rim toward the center of the body. It is obvious that, due to the above given 40 calculation, the field intensity along the line i_6 must equal the intensity along the line i_7 . By the gradual curvature of the cap profile, however, a uniform field distribution is also attained in the insulator sections between these lines.

45 In order to eliminate the overturning moment exerted upon the insulator body, shown in Fig. 1, by the pull of the conducting wire, the wire may, if desired, be passed through two eyes disposed in diametrical relation to each other upon the cap, the conducting wire being secured as usual to the binding post which is provided at the center of the cap.

An advantage of the foregoing structure 55 lies in the fact that the entire insulator body may, if desired, be manufactured in one piece. The dielectric strength of the insulator is then not appreciably lessened by local defects in the material, since the stress to which the insulator is subjected is considerably less for a given voltage than with the known devices. For the same reason, cheaper and more easily worked materials such as earthen ware, stone ware, glass and the like may be employed.

I claim:

1. In a high tension electrical insulator, the combination comprising an umbrella shaped insulating body having an internal bore for the reception of an electrode, an electrode in said bore, a convexly curved 70 metallic cap, constituting a second electrode, so superimposed upon said body as to include a gap with said body, and an insulating medium in said gap, the said insulating body and the said cap being so shaped and 75 arranged with respect to each other that the shortest distance lines drawn from given points on said cap to the surface of the first named electrode and extending within the insulator are approximately proportional to 80 the average dielectric coefficients measured along said lines.

2. In a high tension electrical insulator, the combination comprising an umbrella shaped insulating part having an axial bore, 85 an electrode arranged within said bore, a cap of conducting material forming the other electrode and being so shaped and arranged as to contact the rim of said part and to include a gap therewith which continuously increases from said rim toward the axis of said body, the said cap being spaced from the first named electrode by a definite distance in axial direction, and a gaseous insulating medium within said gap, 90 the ratio of said distance to the radial distance between the rim of said part and said electrode being substantially equal to the ratio of the average dielectric coefficients 95 measured along the respective lines of said distances.

3. In a high tension suspended electrical insulator, the combination comprising an umbrella shaped insulating body traversed by an internal bore, a central draw-bolt positioned in said internal bore constituting one electrode and being arranged so as to transmit the load forces to the upper surface of said insulating body, a convexly curved metallic cap fitted over said insulating body so as to include a gap therewith and to engage and support the rim of said body, and an insulating medium in said gap, the said insulating body and the said cap being so shaped and arranged with respect to each other that the shortest distance lines drawn 105 from given points on said cap to the surface of the first named electrode and extending within the insulator are approximately proportional to the average dielectric coefficients 110 measured along said lines.

4. In a high tension suspended electrical insulator, the combination comprising an umbrella shaped insulating body having an arched cross-section and traversed by an internal bore, a central draw-bolt positioned in said internal bore constituting one electrode and being arranged so as to transmit 125

the load forces to the top of the said arched insulating body, a convexly curved metallic cap fitted over said insulating body so as to include a gap therewith and to engage the rim of said arched body, thereby supporting the base of the same and maintaining it in position even if broken, and an insulating medium in said gap, the said insulating body and the said cap being so shaped and ar-

ranged with respect to each other that the 10 shortest distance lines drawn from given points on said cap to the surface of the first named electrode and extending within the insulator are approximately proportional to the average dielectric coefficients measured 15 along said lines.

In testimony whereof I affix my signature.
ALEXANDER SIMON.
